UTILITY STAND

Filed April 15, 1929

Inventor
John Skultety

Fred H. Taylor

Attorney

UNITED STATES PATENT OFFICE

JOHN SKULTETY, OF LOS ANGELES, CALIFORNIA

UTILITY STAND

Application filed April 15, 1929. Serial No. 355,135.

My invention relates to utility stands adapted for many uses, such as a table, piano stool, Christmas tree stand, camping outfits, radio tables and the like, which is collapsible, so that certain parts may be removed, and conveniently stored and packed, said invention being more particularly an improvement 5 on my prior application, Patent Number 1,724,320, issued August 13, 1929.

10 It accordingly is an object of my invention to provide a novel form of utility stand having a framework consisting of upper and lower members, with which are associated a leg supporting means relatively movable to

15 said members, there being associated with said members a supporting device, or post preferably removable therefrom, means being provided on said post and on said leg supporting means to prevent movement 20 thereof when the stand supports considerable weight.

A further object of my invention is to provide a novel form of article supporting means, including a seat or table top, preferably hinged to, and at the same time removable from an extensible means for elevating said seat or table top, and locking the same in position on said extensible means, there being also provided a novel form of lock, preferably of gravitational form, for automatically locking said extensible means in extended position.

The above, and further objects and advantages of my invention, as will be herein- 35 after more fully set forth, I attain by the construction described in the specification and illustrated on the drawings, forming a part of my application.

Reference is had to the accompanying 40 drawings, in which similar reference characters denote similar parts. In the drawings,

Fig. 1 is a side elevational view of my invention provided with a table top,

45 Fig. 2 is a bottom plan view, on a somewhat enlarged scale, of the table top,

Fig. 3 is a side elevational view of the supporting post or standard and stem, including the lock, removed from the frame- 50 work of the device,

Fig. 4 is a top plan view of one of the hinge portions associated with the top of the supporting stem.

Fig. 5 is a bottom plan detail view of the flange of the post or stand, illustrating one of the plural means for preventing movement of the framework, 35

Fig. 6 is a fragmentary vertical sectional view, on an enlarged scale, illustrating the means for preventing the removal of the 60 stem from the post or standard,

Fig. 7 is a fragmentary top plan view of the gravitational lock for the stem and fulcrum means,

Fig. 8 is an enlarged cross-sectional view, 65 taken on the line 8—8, Fig. 4, and

Figs. 9 and 10 are enlarged fragmentary detail views illustrating the means by which the flange of the post is locked and unlocked, so that said post may be removed from its 70 framework.

Describing my invention more in detail, I provide a framework, designated generally by the numeral 2, comprising an upper member preferably formed of vertical ring sections 4, flanged as at 6, and to which are pivoted leg braces 8, which may be three in number, the pivot pins 10 holding said ring sections together. 75

The lower member 12 of the framework 2 is preferably in the form of a ring or anulus and has projected therefrom the extensions 14, which may be riveted thereto as shown in Fig. 1, and on each end of said extensions is provided a stop 16, which may be 85 in the form of a hook, to limit the outward movement of the leg braces 8, said extensions forming also a guiding means for said braces. In case three ring sections are used, three braces and three extensions 14 are provided. 90

Pivoted to the extensions 14, as at 18, and to the braces 8, as at 20, are the supporting means or legs 22, said legs on their lower ends being provided with feet 24, which may be in 95 the form of upwardly curved portions, making an ornamental appearance. The legs, braces, and extensions are twisted, as shown in Fig. 1, for the sake of rigidity and also to add to the attractiveness of the device. The 100

full lines in Fig. 1 show the legs and braces in full extended position, the dotted lines illustrate the collapsed position.

The supporting device, which bears the article supporting or bearing means, such as a table or seat, comprises a hollow post 26, provided with a flange 28, either integral or associated with said post in any desired manner, said flange, when the device is in use, resting upon the ring sections 4. See Figs. 1 and 9.

Positioned within the post or standard 26 is a preferably hollow (for the sake of lightness and economy of manufacture) stem 30, which stem has on its lower portion a stop of any preferred form, such as a sleeve 32, forced over said end, which stop prevents the removal of the stem 30 from the post 26 by engaging with the shoulder 34 of said post, as seen in Fig. 6.

The stem 30 has preferably an upper reduced end 36 (Fig. 4) for receiving the flat lower stationary hinge portion 38, said hinge portion being preferably forced over said reduced end portion, although said hinge portion may be associated with the stem 30 in any other manner in practice found desirable. The hinge portion 38 is positioned in off set relation with the stem 30 for a purpose presently to be described, the holes 40 being also provided therein, the purpose thereof also to be described later.

The stem 30 is adapted to be extended within the post 26 so that the table top or seat may be raised or lowered at will. For this purpose a lock must be provided to hold said stem in position, and I have provided a gravitational lock 42. Said lock comprises a preferably ring-shaped portion 44, positioned about said stem and concentric therewith, said ring portion having extended therefrom a preferably bent rod or lever operating means 46, which lever or rod is adapted to be positioned within the fulcrum 48 (Figs. 1 and 7) associated with one of the upper ends 50 of the leg braces 8 in any preferred manner, which fulcrum may in practice take any form, in the present instance comprising a pair of curved and outwardly flared lips, which permit the arm or rod 46 to shift toward or away from the stem 30, thus providing a shifting fulcrum. By lowering the outer end of the lever or rod 46, the ring 44 is positioned concentrically with relation to the stem 30, and said stem, including the seat or table, may be raised. Dropping said lever or rod, permits the ring 44 to fall by gravity, thus wedging said ring to said stem, and providing an effective lock so said stem (and seat or table) cannot be raised relatively to the device.

To prevent relative movement of the leg braces 8 and the post 26, the lower side of the flange 28 may be provided with teats or projections 52. See more particularly Figs. 5 and 6. Said teats or projections engage the inner sides of the ring sections 4, when the

flange 28 is positioned thereon, the post 26 then extending through said ring sections, or upper member and the hole in the lower flat annulus or lower member 12, as seen in Fig. 1.

As an additional means for preventing movement where heavy weight is placed upon the device, the curled ends 50, which also add to the attractiveness of the device, are adapted to engage with and securely lock the flange 28 in position. See Figs. 9 and 10. In the former figure the leg braces 8 are locked with the flange 28; in the latter they are out of engagement, and the stem 30, and post 26, may be removed from the framework, as indicated by the dotted lines in said figure.

The table top or seat 54 has positioned on the underside thereof a block 56 of any preferred shape or size and sufficient to receive the upper hinged portion 58, (see Fig. 2) which hinge portion may be secured to said block in any preferred manner, as by the screws 60, the hinge portion 58 having hook-shaped hinge elements 62, which may be positioned within the openings 40 (Fig. 4), and hence may be removed therefrom, so that the table top or seat 54 may be swung to one side so it will occupy a small space, or said seat or table top be entirely removed and stored, the hinge elements 62 being so shaped as to prevent inadvertent removal. A spring clamp 64 (Figs. 1 and 2) engages the outer edge of the lower or stationary hinge portion 38, to lock said seat top or table top in position on the device, the stem 30 being positioned in offset relation with said hinge portion so that the seat or table top will be accurately centered with respect to the stand.

In case the device is to be used as a Christmas tree holder, the post 26, with its stem and hinge portion, as well as the table or seat top are removed, and the thumb-screws 66 are used to hold and center the tree in position.

While I have thus described my invention with great particularity, it will be clear that the same may be modified throughout a wide range. I accordingly do not propose to be limited to the exact details of construction shown and described, but reserve the right in practice to make any and all modifications thereof that fall within the scope of the appended claims.

I claim as my invention:

1. In a utility stand, an upper vertical support, a lower horizontal ring support, a set of braces pivoted to said upper support, a set of combined stop and guiding extensions projecting from said lower support, said extensions being adapted to guide and limit the outward movement of said braces, a set of legs, each pivoted to each of said braces and said extensions, a removable standard having its lower end positioned in said lower support, a circular flange associated with the upper end of said standard and positioned on said upper support, means on said flange

adapted to engage said upper support to prevent movement of said standard, means on the upper end of each of said braces for engaging said flange for additionally preventing movement of said standard, a stem adjustably positioned in said standard, and an article supporting member associated with said stem.

2. In a device of the class described, a framework comprising upper and lower members, a flanged supporting post removably associated with both of said members, a set of collapsible leg and brace members associated with said upper and lower members, and means associated with the tops of each of said brace members for locking said flange to said upper member when said leg and brace members are in extended position, and for unlocking said flange when said leg and brace members are collapsed so said post may be removed from said upper and lower members.

3. In a device of the class described, a framework comprising upper and lower members, a set of brace and leg members movably associated with said upper and lower members, a supporting post associated with said upper and lower members, an extensible supporting stem in said post, a gravitational lock for holding said stem in extended position, and fulcrum means on the upper end of one of said brace members for permitting said lock to be operated, irrespective of the movement of said brace and leg members.

4. In a device of the class described, a framework comprising upper and lower members, a set of brace and leg members, said brace members being each pivoted to said upper member and to each of said leg members, extensions on said lower member, stop means on each of said extensions adapted to be engaged by said brace members, means for pivoting said leg members to said extensions, an extensible supporting device associated with said upper and lower members, a gravitational lock associated with said device, a fulcrum element on the upper end of one of said brace members, and means associated with said lock and said element whereby a shifting fulcrum may be provided for said lock.

5. In a device of the class described, a framework comprising upper and lower members, means associated with both of said members for supporting said framework, a supporting post extending through said upper and lower members, an extensible supporting stem in said post, means on said stem for preventing the removal of said stem from said post, and means associated with said framework and said stem for locking said stem in extended position.

6. In a device of the class described, a framework comprising upper and lower

members, collapsible supporting means associated with both of said members, a supporting device removably associated with said upper and lower members, and plural means associated with said device, said collapsible supporting means and said framework for preventing movement of said device and said collapsible means, when the latter is in extended position.

7. In a device of the class described, a framework comprising upper and lower members, supporting means associated with each of said members for supporting said framework, a hollow post associated with said upper and lower members, a supporting stem extensible in said post, means associated with said stem and said post adapted to coact to prevent the removal of said stem from said post, and an article bearing support removably hinged to the top of said stem.

8. In a device of the class described, a framework comprising upper and lower members, means associated with said members for supporting said framework, extensible supporting means removably associated with both of said members, locking means associated with said extensible means for locking the latter in extended position, an article supporting member, and a hinged clamp for removably hinging said article supporting member to said extensible means and for clamping said article supporting member in position.

In testimony whereof I have signed my name to this specification.

JOHN SKULTETY.
